CAN HOLDER AND SERVER

Marion William Janowski, Bakersfield, Calif.

Application January 30, 1936, Serial No. 61,585

4 Claims. (Cl. 65—61)

This invention relates to a can holder and server, capable of use with cans which contain various commodities and for example beer.

It is aimed to provide a novel construction capable of manufacture from a single blank of metal or other material, expeditiously and inexpensively.

The more specific objects and advantages will become apparent from a consideration of the description following taken in connection with accompanying drawing illustrating an operative embodiment.

In said drawing:—

Figure 1 is a view in front elevation of the improved device;

Figure 2 is a view taken substantially on the line 2—2 of Figure 1;

Figure 3 is a perspective view of the device and

Figure 4 is a plan view of the blank from which the device is constructed.

Referring specifically to the drawing wherein reference characters designate like or similar parts, the device is initially struck in a single blank from sheet metal or other material, in the form disclosed in Figure 4.

The device consists of a base plate 10 from which an upright wall 11 rises, such wall at the lower edge resting on the base plate 10 and being connected thereto by a neck 12 upbent at a right angle to the wall 11 and returned over the base plate, thereby insetting the wall 11 in the margin of the base plate.

Said wall or upright 11 may be of any desired width or configuration but preferably is arcuate and widened at the lower portion as at 13 and extends into a narrower portion 14. From the portion 14, the portion 15 is bent outwardly into the form of a handle, whose free end as at 16 may be welded or soldered to the wall 11.

A struck-up tongue 17 is provided on the base plate 10 and a struck-out hook 18 is provided at the junction of the portions 14 and 15, the same extending over the base plate.

The device is adapted to be used, for example, to hold a can such as that suggested in dotted lines at 19 which is of the type in which beer is marketed, although no limitation is to be implied to the use with this particular material. Such a can has its top and bottom depressed as shown at 19 and 20, respectively.

In the use of the device, the can is disposed with its bottom resting on the tongue 17 and hence the latter extends into the depression 20.

The can is then depressed, accordingly depressing the tongue against its tension, to enable the can to engage under the hook 18, and the latter to hook over the marginal edge of the top of the can. The can will thus be removably and resiliently held in place through the spring tension of the tongue 17, urging the can into tight engagement with the hook 18, lateral displacement of the can being avoided by contact of the latter with the widened wall portions 13.

Various changes may be resorted to provided they fall within the spirit and scope of the invention.

I claim as my invention:—

1. A can holder of the class described, having a base, a relatively narrow wall rising from one side of the base, a hook on said wall for retaining engagement by a can or the like, and an upstruck resilient tongue on said base to engage a can or the like and urge the same toward and maintain it in engagement with said hook.

2. A can holder of the class described, having a base, a relatively narrow wall rising from one side of the base, a hook on said wall for retaining engagement by a can or the like, and an upstruck resilient tongue on said base to engage a can or the like and urge the same toward and maintain it in engagement with said hook, said base having a returned portion integrally engaging said wall.

3. A holder for a can or the like made from a single blank of material having a base, and upstruck resilient tongue on said base, a return portion over said base, a wall rising from said return portion and being arcuate adjacent the base, said wall having a struck-out hook engageable with a can or the like, and a handle extending from said wall in a direction opposite to the hook.

4. A holder for a can or the like made from a single blank of material having at one end an enlarged portion comprising a base, an upstruck resilient tongue on said base, a narrow return portion over said base, a wall portion rising from said return portion said wall portion being relatively wide adjacent to the base and tapering and its extended portion relatively narrow, an outstruck hook on said extended portion for engagement with a can or the like, and the extremity of said extended portion providing a handle extending from said extended portion in a direction opposite to the hook.

MARION WILLIAM JANOWSKI.
